CIGARETTE, CIGAR, AND THE LIKE

Frederick Schallgruber, Bogota, Colombia

Application May 16, 1938, Serial No. 208,273

2 Claims. (Cl. 131—52)

My invention relates to new and useful improvements in cigarettes, cigars and the like.

Heretofore various igniting devices have been secured or attached to cigarettes, cigars or the like for igniting the same as they were withdrawn from a package or by other operations. So far as I have been able to ascertain, the igniting element or medium was secured in direct contact with the smoking content of the cigarette in order to ignite the same. One of the paramount objections to cigarettes having igniting elements secured thereto has been that the fumes generated by the chemical composition of the igniting element were mixed with the tobacco smoke when the smoker began to draw air through the cigarette to assist in igniting the combustible or tobacco content thereof.

One of the principal objects of my invention is to provide a cigarette equipped with an igniting element so arranged and constructed to be maintained in an isolated position from the end of the cigarette until such time as the fumes and gases therefrom are substantially exhausted thereby eliminating the mixture of the same with the tobacco smoke.

Another object of my invention is to provide a cigarette of the above described character having an igniting element attached thereto so arranged and constructed as to be automatically moved to an isolated position before the same is ignited, thereby preventing the fumes and gases from said element entering the cigarette during the lighting operation thereof.

A further object of my invention is to provide a cigarette of the above described character wherein the igniting element attached to the end of the cigarette is automatically ignited upon removal of a cigarette from a package.

A still further object of my invention is to provide manually operable means for igniting the igniting element and also functioning to isolate said element from the tobacco in advance of the igniting of said element.

Still another object of my invention is to provide a cigarette equipped with an igniting element composed of a plurality of combustible materials one ignitable by the other, the latter being of a content similar to the smokable content of the cigarette.

Other objects and advantages will be apparent from the following description, appended claims and annexed drawing.

Referring to the drawing wherein like reference characters designate like parts throughout the several views:

Fig. 1 is a perspective view of a package of cigarettes in partly opened condition and wherein a plurality of my improved cigarettes are illustrated, one of said cigarettes being illustrated in one of the initial igniting steps. 5

Fig. 2 is a fragmentary sectional view of a package of cigarettes illustrating one of my cigarettes contained therein, the same being shown partly in section.

Fig. 3 is a fragmentary sectional view showing a 10 step in the igniting operation.

Fig. 4 is a similar view to Figure 3 illustrating another step in the igniting operation.

Fig. 5 is a fragmentary sectional view illustrating a final step in the igniting operation. 15

Fig. 6 is an end elevation of one of my improved cigarettes.

Fig. 7 is a plan view of the igniting element.

Fig. 8 is a modified form of my invention illustrating the member for igniting, the igniting element having one end attached to the base of a package or container whereby the igniting element is automatically ignited upon withdrawal of the cigarette from the package. 20

Fig. 9 is a fragmentary perspective view of the 25 lower end of a cigarette illustrating a modification of my invention.

Fig. 10 is a detail sectional view of the modification illustrated in Figure 9.

Fig. 11 is a fragmentary perspective view of 30 another modification of my invention.

In practicing my invention, in the preferred form illustrated in Figures 1 to 7 of the drawing, I provide a cigarette package 5 fashioned on one of the outer faces thereof with a striking element 6 whereby the igniting elements 7 attached to the ends of the cigarettes 8 are ignited. 35

The igniting elements 7 each comprise a disk 9 hingedly secured within the end of a cigarette and fashioned with a plurality of perforations 10. 40 The inner face of the disk has centrally secured thereon a body of inflammable material 11, for instance sulfur or the like, capable of being ignited by frictional engagement with the striking surface 6. Surrounding said disk and maintained on said disk through the medium of the perforations 10 is a coating of combustible material 12 similar to the smokable content 13 of the cigarette, for instance tobacco. 45

When the cigarettes are contained within the 50 package 5 the disk is maintained in closed position as illustrated in Figures 1 and 2 of the drawing. Upon extraction of a cigarette from the package the disk, through the medium of the fingers, is moved to an open position as illus- 55

trated in Figure 3. In this position, the striking element 6 formed on the package 5 is brought into engagement with the inflammable material 11 contained on the inner face of the disk and the 5 disk moved to a position laterally of the longitudinal axis of the cigarette, and by pressure of a finger applied to the outer face of the disk, the disk and cigarette moved over the surface of the striking element 6 thereby causing the igniting 10 of the inflammable material 11. The burning of the inflammable material 11 causes the combustible material 12 to become ignited thereby and upon the material 11 becoming extinguished, the disk is permitted to hinge downwardly there- 15 by causing the still burning material 12 to engage and ignite the tobacco 13. The perforations 10 in the disk serve to permit air to be sucked through the cigarette to assist in the igniting of the tobacco. It is to be understood that the disk 20 9 is constructed of a noncombustible material and that after the end of the cigarette has become ignited the material 12 may be extinguished by rubbing the same against the surface on the package or the like. The disk becomes severed from 25 the end of the cigarette after the cigarette has been consumed a sufficient distance to release the hinge connection secured within the wrapper.

In the modified form illustrated in Figure 8, the disk 15 has formed therein a pair of spaced 30 slots 16, one on each side of the highly inflammable material 17. A strip 18 is trained through said slots and over the material 17. One end of the strip is secured to the base of the package or container and the other end formed on the outer 35 face thereof with a striking surface or element 19. In operation, as a cigarette is withdrawn from the package the disk 15 is caused to move downwardly by the frictional engagement of the strip 18. Continued movement of the cigarette 40 relative to the strip 18 causes the strip to slide through the slots 16 and over the outer face of the body 17. As this movement continues the striking surface or element 19 will engage the body 17 and ignite the same causing a subsequent igniting of the surrounding body of tobacco. The end of the cigarette is then ignited 45 in the same manner illustrated and described in the preferred form.

In the modified form illustrated in Figures 9 and 10, the disk is provided with a central aperture 50 and the highly inflammable body of material 20 extends therethrough for engagement with the striking element 21 carried on the inner

face of the strip 22 in the same manner as in the instance of the form illustrated in Figure 8. A suitable guide 23 or strap is secured to the outer face of the disk for guiding the strip over the face of the body of material 20. In this form, 5 the strip may be drawn over the surface of the material 20 by means of the fingers or by attachment to the cigarette package.

In the modified form illustrated in Figure 11, one end of the strip 25 is fashioned with a pull 10 tab 26 whereby the same may be grasped and the strip pulled over the surface of the highly inflammable body of material in the same manner as in the instance of the modified form illustrated in Figures 9 and 10. The pull tab 26 is adapted 15 to be folded over the disk 27 to form a closure for the end of the cigarette 28.

From the foregoing it will be apparent that by positioning the disk below the end of the cigarette before igniting the material contained 20 thereon, the gases from the highly inflammable material are permitted to be exhausted before the disk is moved into engagement with the end of the cigarette for lighting the same through the medium of the slow burning combustible material 25 or tobacco secured thereon.

What I claim is:

1. A device of the character described, comprising, in combination, a cigarette or the like, a closure for one end of said cigarette having a 30 body hingedly supported by said cigarette and provided with slow and fast burning combustibles, said fast burning combustible adapted to be ignited in isolated position from the end of said cigarette for effecting ignition of said slow burning combustible whereby said slow burning combustible ignites said cigarette upon engagement of said closure with said cigarette. 35

2. A device of the character described, comprising, in combination, a cigarette or the like, a disk 40 for closing one end of said cigarette and hinged to the latter, said disk having an inner face provided with slow and fast burning combustibles mounted thereon and operable away from the end of said cigarette to enable said fast burning combustible to be ignited in isolated position from the end of said cigarette for effecting ignition of said slow burning combustible whereby said slow burning combustible will ignite said cigarette upon engagement of said disk and said end of the cigarette. 45

FREDERICK SCHALLGRUBER.
